UNITED STATES PATENT OFFICE.

GEORGE WASHINGTON ADAMS, OF SAN ANTONIO, TEXAS.

CONCRETE, MORTAR, AND PLASTER MIXER.

Application filed July 16, 1926. Serial No. 122,912.

This invention relates to mixers for concrete, mortar and plaster of the type utilizing drums adapted to be operated by hand and more particularly is directed to 5 the type of mixer patented by me April 22, 1924, No. 1,490,952.

An object of the invention is the provision of a concrete mixer including an oscillatory drum in which are provided staggered grate rods and vanes adjacent the walls of the drum which will produce a concrete of stronger compressive strength with less manual effort.

A further object of the invention is the provision of a mixer including a manually oscillated drum which is equipped internally with staggered grate rods running longitudinally in spaced relation of the drum and supported by staggered transverse bars.

Another object of the invention is the provision of steel supports for a mixer by which it is possible to quickly elevate the mixer for discharging the mixture of concrete into a wheel barrow, the steel supports 25 eliminating the usual temporary wooden supports.

A still further object of the invention is the provision of a mixer having a plurality of steel platforms or steps for the operator to use so that the mixer may be very conveniently operated.

This invention will be best understood from a consideration of the following detailed description, in view of the accompanying drawings forming a part of the specification; nevertheless it is to be understood that the invention is not confined to the disclosure, being susceptible of such changes and modifications which shall define no material departure from the salient features of the invention as expressed in the appended claims.

In the drawings:

Figure 1 is a side view of a mixer constructed in accordance with the principles of my invention and partly broken away to show the interior.

Figure 2 is a front end view with the drum partly broken away.

Figure 3 is a section along the line 3—3 of Figure 1.

Referring more particularly to the drawings, 10 designates a table or frame which is carried at its forward end by means of U-shaped legs 11 and at the rear end by wheels 12. The legs are supported in chan-

nel members 13 carried by rectangular shaped metal members 14. A brace bar 15 bolted to the lower ends of the supports 14 is adapted to aid in maintaining said members in spaced relation. A pair of stands 16 are located at the rear and beneath the wheels 12 and are provided with a slotted bar 17 which is adapted to receive a portion of the wheel 12.

A pair of spaced standards 18 are secured to the sides of the frame 10 and are provided with bearings 19 at their upper ends for trunnions 20 which are secured to the side walls of an oscillatable drum 21. The drum is oscillated by means of a handle 22 which is secured in any approved manner to the interior of the drum and projects outwardly as shown in Figure 1. The standards 18 are braced by diagonally disposed members 23 which are connected to the upper ends of the standard and to the outer ends of the frame by metal plates 24.

Projecting laterally from the sides of the frame are platforms 25 supported by brackets 26 secured to the frame. Angularly bent reinforcing bars 30 are also connected to the frame and are extended upwardly and to a point intermediate the ends of the standards 18, at opposite sides of the drum 21. A second platform or foot rest 31 is mounted intermediate the ends of the mixer.

The angularly disposed reinforcing bars 30 are further reinforced by the metal bars 33 which are connected between the bar 33 and a bar 34 which has an attachment 35 at its upper end adapted to engage the reinforced end of the frame 36 for the discharge opening of the drum 21. A step or platform 31^a is carried by the bar 33. Means are provided in the form of a U-shaped cleat 38 and a bolt 39 for securing a tongue to the mixer in order to aid in the conveying of the same. A hand grip 40 secured to the front end of the frame is located adjacent the tongue securing means just described.

Located transversely of the interior of the drum and in spaced relation and also in a plane which passes through the lower end of the opening to the drum are pairs of transverse supporting bars 41 and 42 located adjacent the bottom of the drum and a pair of supporting rods 43 and 44 located adjacent the top of the drum. Running

longitudinally of the top of the drum are a plurality of grate bars 45 which are secured to the top edges of the supporting rods 43 and 44 while grate bars 46 are secured to the lower edges of the bars 43 and 44 and in staggered relation with the upper bars 44. Similarly adjacent the bottom of the drum are a plurality of grate bars 47 secured to the top edges of the transverse supports 41 and 42 while grate bars 48 are secured to the lower edges of said supporting bars. The supporting bars are provided with flanges 49 which are secured to the side walls of the drum.

15 Vanes 50 have their ends disposed in different planes and are located adjacent the sides of the drum. These vanes are supported above the bottom of the drum. Small vanes 52 are carried by cleats 53 at the rear of the drum and adjacent the bottom.

The drum 21 is manually operated by the handle 22 which projects forwardly of the open end 36 and the drum is oscillated on the trunnions 20 carried by the standards 18. The concrete which must pass through the grate bars 45 to 48 inclusive is thoroughly mixed with the water and other materials so that a concrete of stronger compressive strength is obtained and a better and more thoroughly mixed concrete is provided due to the fact that the concrete must pass thru the staggered grate bars. Even when the drum is tilted the concrete must be acted upon by the vanes 50 and 51 before the same is discharged from the drum, so that the concrete will be given an additional mixing at this time and be directed towards the open end.

40 What I claim is:

1. In a device of the character described, a drum mounted for oscillation about a fixed axis, and having a normally open end, supporting bars secured to the side walls of the drum and extending transversely of the same, other supporting bars located at a higher level than the first mentioned supporting bars, the ends of the supporting bars being secured to the side walls of the drum, and grate bars secured to the supporting bars and extending longitudinally of the drum.

2. In a device of the character described, a drum mounted for oscillation about a fixed axis, and having a normally open end, supporting bars secured to the side walls of the drum and extending transversely of the same, other supporting bars located at a higher level than the first mentioned supporting bars, the ends of the supporting bars being secured to the side walls of the

drum, and grate bars secured to the supporting bars and extending longitudinally of the drum, alternate grate bars being disposed upon opposite sides of the supporting bars.

3. In a device of the character described, a drum mounted for oscillation about a fixed axis, and having a normally open end, supporting bars secured to the side walls of the drum and extending transversely of the same, other supporting bars located at a higher level than the first mentioned supporting bars, the ends of the supporting bars being secured to the side walls of the drum, and grate bars secured to the supporting bars and extending longitudinally of the drum, the grate bars secured to a particular group of supporting bars being located in staggered relation.

4. In a device of the character described, a drum mounted for oscillation about a fixed axis, and having a normally open end, supporting bars secured to the side walls of the drum and extending transversely of the same, other supporting bars located at a higher level than the first mentioned supporting bars, the ends of the supporting bars being secured to the side walls of the drum, and grate bars secured to the supporting bars and extending longitudinally of the drum, and vanes disposed adjacent the bottom and side walls of the drum.

5. In a device of the character described, a drum mounted for oscillation about a fixed axis, and having a normally open end, supporting bars secured to the side walls of the drum and extending transversely of the same, other supporting bars located at a higher level than the first mentioned supporting bars, the ends of the supporting bars being secured to the side walls of the drum, and grate bars secured to the supporting bars and extending longitudinally of the drum, and angularly bent vanes located above the bottom of the drum.

6. In a device of the character described, a drum mounted for oscillation about a fixed axis and having a normally open end, supporting bars secured to the side walls of the drum and extending transversely of the same, other supporting bars located at a higher level than the first mentioned supporting bars, the ends of the supporting bars being secured to the side walls of the drum, and grate bars secured to the supporting bars and extending longitudinally of the drum, the grate bars connected to the upper supporting bars, and pairs of vanes disposed above the bottom of the drum and adjacent the side walls of the drum.

GEORGE W. ADAMS.
